CROSS LINE RELIEF MECHANISM FOR
REVERSIBLE HYDRAULIC MOTOR
Francis H. Tennis, Milwaukee, Wis., assignor to Hydraulic
Unit Specialties Company, Pewaukee, Wis., a corpora-
tion of Wisconsin
Filed Oct. 10, 1962, Ser. No. 229,601
3 Claims. (Cl. 137—491)

This invention relates to hydraulic control instrumentality and refers more particularly to a cross line relief mechanism for a hydraulic system of the type comprising a reversible hydraulic motor and a control valve by which operation of the motor is governed, which cross line relief mechanism provides for transfer of hydraulic fluid from one side of the motor to the other when the control valve is in its "hold" position and there is a fluid pressure difference across the motor which is in excess of a predetermined high value.

A cross line relief mechanism is employed in a hydraulic system wherein a reversible hydraulic motor is connected with a load that tends to exert high inertia forces upon the motor, such as the laterally swinging boom of a large crane, the carriage of a power shovel, or the like. Such a motor is set in motion by shifting a control valve connected therewith to an operating position at which the valve directs pressure fluid from a source thereof to one side of the motor and at the same time permits return fluid from the other side of the motor to flow back to a reservoir or the like. When the control valve is shifted back to its neutral or "hold" position, it cuts off the motor from both the pressure fluid source and the reservoir, in effect blocking the lines that connect the motor with the control valve. If the load driven by the motor has high inertia, it tends to keep the motor moving in the direction in which the motor had been driving the load, so that the motor tends to push return fluid into one of its lines connected with the control valve and to draw a void in the other line.

In the absence of some sort of relief mechanism the motor cannot move when its lines are thus blocked, and the pressure developed in the line into which fluid is being urged by the inertia load could reach dangerously high magnitudes. A cross line relief mechanism prevents this unsafe condition by permitting fluid to bleed from one to the other of the lines connected with the motor when the fluid pressure difference between the lines exceeds a predetermined high value.

The effect of such a cross line relief mechanism is to afford a damped deceleration of the inertia load after the control valve is moved to its neutral or "hold" position, due to the throttled flow of fluid from one side of the motor to the other provided for by the cross line relief mechanism.

Heretofore it has been conventional in cross line relief mechanisms to provide two transfer passages through which the two lines or service passages that connected a control valve with its associated motor were communicable with one another, each such transfer passage providing for flow of fluid in only one direction. The reason there had to be a transfer passage for each direction of cross line fluid flow was that communication through each transfer passage was controlled by a more or less conventional high pressure relief valve through which fluid could flow in only one direction.

2

By contrast it is an important object of the present invention to provide a cross line relief mechanism comprising a body having a pair of ports, each connectable with one side of a reversible hydraulic motor, and having only a single relief valve controlled transfer passage through which pressure fluid can flow in either direction, from either body port to the other.

Another object of the present invention is to provide a cross line relief mechanism having a pair of motor ports, a single transfer passage through which fluid can flow in either direction between the motor ports, and a pair of relief valve units, each having poppet mechanism to control communication between one of the motor ports and the transfer passage.

A further object of this invention is to provide a cross line relief mechanism of the character described, which affords unusually smooth and effective deceleration of an inertia load.

Still another object of this invention is to provide a cross line relief mechanism of the character described which can be embodied in an accessory or attachment that is adapted to be secured to the body of a conventional hydraulic control valve of either the integral type or the so-called stacked or sectional type, to adapt such valve for use with a reversible hydraulic motor that drives a high inertia load.

It is also among the objects of this invention to provide a cross line relief mechanism of the character described that can be manufactured easily and inexpensively, can be readily installed in a hydraulic system, and is efficient and dependable in operation.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention, constructed according to the best mode so far devised for the practical application of the principles thereof, and in which:

FIGURE 1 is a sectional view of a cross line relief mechanism embodying the principles of this invention installed, as an accessory or attachment, upon a hydraulic control valve of the sectional type and connected with a double acting hydraulic cylinder, the cross line relief mechanism being shown in an inoperative condition such as obtains when there is no pressure difference across the cylinder; and

FIGURE 2 is a fragmentary sectional view on an enlarged scale of the cross line relief mechanism illustrated in FIGURE 1, shown in its operative condition in which it is relieving a substantially high pressure on the left hand side of the cylinder.

Referring now more particularly to the accompanying drawings, the cross line relief mechanism 5 of this invention is shown as embodied in an attachment for one section of a more or less conventional hydraulic control valve 6 of the sectional or stacked type, which valve is connected with a reversible hydraulic motor such as a double acting hydraulic cylinder 7. It will be understood, however, that the cross line relief mechanism 5 could

equally well be incorporated in the body of the valve itself, or could be formed as an independent, self-contained unit, adapted to be mounted at a location apart from the control valve. Obviously, too, when made as an attachment or accessory for a control valve it could be used with valves of other than the sectional or stacked type herein illustrated.

The control valve 6 to which the cross line relief mechanism 5 is here shown attached comprises a body 8 in which there is an open center or through passage 9 connectable with a source of hydraulic fluid under pressure, return fluid passage means 10 which opens to an outlet (not shown), and a pair of motor ports 11, each connectable by means including a duct or line 12 with one side of the double acting cylinder 7. As is conventional, the valve body 8 is so formed as to be adapted for assembly with other similar bodies that are connectable with other hydraulic motors, and with end sections (not shown) which provide for connection of the open center passage 9 with a pump or the like and of the return fluid passage means 10 with a reservoir or the like.

The valve body 8 has a bore 13 therein in which a spool or valve element 14 is slidable in opposite directions from a neutral position in which it is shown to either of a pair of operating positions. The open center passage 9 intersects the spool bore 13 intermediate the ends thereof and is so formed that when the spool 14 is in its neutral position pressure fluid flowing in the open center passage 9 moves through a portion of the spool bore and to the valve body outlet. When the spool is shifted to one or the other of its operating positions, however, it blocks the open center passage 9 at the spool bore and causes pressure fluid to be diverted to a bridge passage 15 which communicates with the open center passage upstream from the spool bore and the legs of which communicate with the spool bore at zones 16 spaced to opposite sides of its intersection with the open center passage. Depending upon the operating position in which the spool has been placed, pressure fluid from the bridge passage 15 is permitted to flow through another small portion of the spool bore 13 to one or the other of a pair of service passages 18 which communicate the motor ports 11 with the spool bore at zones 19 of the latter spaced axially outward from its zones 16 of intersection with the legs of the bridge 15. Thus in each operating position of the spool 14 it diverts pressure fluid into the bridge passage 15 and to a selected side of the double acting cylinder 7 by way of one of the ducts or lines 12 that connect the cylinder with the motor ports 11 in the valve body. At the same time, the spool directs return fluid from the motor, brought to the other motor port 11 by way of the other line 12, to the return fluid passage means 10, which has two branches that intersect the spool bore near the opposite ends thereof.

In the present instance the control valve is shown as having incorporated therein anticavitation means 21 of the type disclosed in the copending application of Francis H. Tennis, Serial No. 191,163, filed April 30, 1962, comprising a short passage 22 connecting each service passage 18 with its adjacent leg of the return fluid passage means 10. Communication through each of the passages 22 is controlled by a check valve 23 of the type that moves in a direction counter to the direction of flow that it permits. Thus if the spool is in one of its operating positions, and if the motor 7 is driven by its load at a rate so high that the piston 24 of the motor is evacuating one side of the cylinder 25 faster than hydraulic fluid can be supplied thereto in the the normal manner, a void tends to be drawn in one of the service passages 18. The check valve 23 adjacent to that service passage then opens to permit additional fluid to be supplied to the evacuating side of the cylinder from the return fluid passage means 10.

For further details of the construction and operation of this void control or anticavitation mechanism refer-

ence may be made to the aforesaid copending application. It will be apparent that this anticavitation feature is not required in many installations in which a cross line relief mechanism is utilized, but it does not in any wise interfere with the cross line relief mechanism 5 or its operation.

The cross line relief mechanism 5 comprises a body 30 which is adapted to be suitably secured to the control valve 6, with one face 31 of the body 30 flatwise abutting that face 32 of the control valve body 8 to which the motor ports 11 open. Extending through the body 30 are service or line passages 33 which form continuations of the service passages 18 in the control valve body when the two bodies are assembled with one another. Each of the service passages 33 opens at one end to the face 31 of the body 30, to provide a communication port 34 that registers with one of the motor ports 11 in the control valve body. An O-ring 35 or similar seal, received in an annular groove opening to the face 31 of the body 30 surrounds each communication port to seal the junction of the two bodies. At its other end each line passage 33 opens to another side of the body 30 at a motor or line port 36 that is connectable with one of the lines or ducts 12 leading to the double acting cylinder.

Fluid flow between the two motor ports 36, for cross line relief, is provided for by a single transfer passage in the body, generally designated 37. The transfer passage 37 is comprised of three passage sections, namely a main section 137 which extends lengthwise between but terminates short of the motor ports 36, and opposite end sections 237 which connect the end portions of the main section 137 with the adjacent motor ports. Each of the end sections 237 has a pair of branches extending at a right angle to one another, with one branch 238 normal to the main section 137 and opening to one end portion thereof through an annular valve seat 38. The other branch of the end section is provided by the line passage 33, which for that purpose is extended inwardly beyond its port 34 to the branch 238 and to be in overlapping relation to the adjacent end portion of the main section 137 of the transfer passage.

By means of the transfer passage, therefore, fluid transferring from one motor port 36 to the other must flow serially through the branch passages 238 and their valve seats 38. Such transfer flow of fluid from one motor port to the other is controlled by a pair of relief valve units 39 mounted on the body so that each is cooperable with one of the valve seats 38. The relief valve units are of the general type disclosed and claimed in the copending application of Francis H. Tennis, Serial No. 153,415, filed November 17, 1961, which illustrates other embodiments of such a valve unit that are as well suited for the purpose as the one illustrated here. In fact, the specific construction and operation of the valve unit here shown comprises the subject of a second copending application of Francis H. Tennis and Donald G. Bethke, Serial No. 202,508, filed June 14, 1962.

Each of the two valve units 39 embodies poppet mechanism that is cooperable with its valve seat 38 and which controls the flow of fluid through the branch passage 238 leading through the seat 38. Moreover, the poppet mechanism of each valve unit is of the type that opens in response to pressures of two different predetermined values, namely a high value and a low value. For this purpose, each valve unit comprises an outer poppet member 42 which is axially slidable back and forth in a cup-like casing 40 having its rim portion screw threaded into a suitably tapped hole in the body opening into one end portion of the main section 137 of the transfer passage at a location coaxially opposite the adjacent valve seat 38. The outer poppet member 42 projects downwardly out of the open end of the casing 40 into the main section 137 of the transfer passage, and its front end opposes and engages the valve seat 38 beneath it to normally block fluid flow through the branch passage 238 leading downwardly from said seat. The casing 40 is formed with a coaxial inner

tubular member and a spring seat member 56 which is axially adjustably threaded into the outer end of the casing.

The cylindrical side wall 41 of the casing surrounds the outer poppet member 42 with substantial clearance to define an annular passage 41' around said poppet member.

The inner tubular member 52 extends forwardly into a rearwardly opening counterbore 53 in the outer poppet, and cooperates with the latter to define a pressure chamber 45 adjacent to the bottom of the counterbore 53. The front portion of the inner tubular member and the cylindrical skirt 44 on the rear of the outer poppet thus comprise a cylinder and piston, but it will be noted that in this instance the usual relationship is reversed, in that the outer poppet member, which as the movable element can be considered the piston, surrounds the inner tubular member which is fixed and may therefore be considered the cylinder.

A coaxial bore 46 that extends through the front portion of the outer poppet member provides for communicating the pressure chamber 45 with what might be termed the system port provided by the adjacent branch 238 of the transfer passage. Hence pressure of fluid in the chamber 45 is normally the same as that of fluid in the system port and at the motor port with which it communicates via the service passage 33. It should be noted that the valve seat 38 has a somewhat smaller diameter than that of pressure chamber 45, and hence the fluid in that chamber tends to maintain the outer poppet member engaged with the seat 38, against the tendency of pressure fluid acting upon the front of the outer poppet member through the seat 38 to move the poppet member off of its seat.

The front end portion 43 of the outer poppet member is shown reduced to a diameter less than the inside diameter of its skirt 44, so as to define a forwardly facing annular surface 49 which is spaced behind its seat engaging surface, and upon which pressure of fluid in the main section 137 of the transfer passage is manifested. The effective area of the surface 49, of course, is somewhat greater than the cross sectional area of the skirt 44 on the rear of the outer poppet member. Hence whenever pressure of fluid in the main section 137 of the transfer passage is at a value above that of fluid in the system port 238 of each valve unit, the fluid in the main section of the transfer passage acts upon the surface 49 of the outer poppet member of the valve unit to cause the poppet mechanism to open the branch or system port 238 and thus communicate the main section 137 of the transfer passage with the motor port associated with said port 238.

The poppet mechanism of each valve unit also includes an inner or pilot poppet 50 which is adapted to open in response to substantially high pressure in the associated line passage 33 or system port 238, and which, when so opened, effects opening of the passage 238 to the main section 137 of the transfer passage, in this case by causing unseating of the outer poppet member 42.

The seat 51 with which the pilot poppet cooperates is formed in the inner tubular member 52 by a portion thereof, spaced behind its front end, that has a reduced inside diameter. The valve element on the pilot poppet that engages this seat comprises an enlarged head 54, the rear face of which serves as a seat for a coiled compression spring 55 by which the pilot poppet is biased forwardly to its seated position. The rear end of the spring 55 reacts against the adjustable spring seat member 56, and the spring is held concentric with the pilot poppet by a rearwardly extending stem portion 57 on the pilot poppet which extends through the convolutions of the spring and is guidingly received in a forwardly opening well 58 in the adjustable spring seat member 56. It will be apparent that the force which the spring 55 exerts upon the pilot poppet, as determined by the

axial position of adjustment of the spring seat member 56, controls the value of fluid pressure in the chamber 45 at which the pilot poppet is unseated. An acorn nut 59 threaded onto the projecting outer end portion of the spring seat member cooperates with another nut 60 to lock the spring seat member against inadvertent rotation and to provide a fluid tight seal.

Opening or unseating of the pilot poppet permits fluid to flow rearwardly out of the pressure chamber 45 through the seat 51, and through radial bores 51' in the inner tubular member, spaced behind the seat 51; thence around the rear of the main poppet member and forwardly into the main section 137 of the transfer passage, through the annular passage 41' provided by the clearance space between the outer tubular member and the outer poppet member. At the same time, flow of fluid from the system port 238 and the line passage 33 into the chamber 45 is restricted to a rate slower than that at which fluid exhausts from chamber 45 through the pilot poppet seat, by a flow restricting plunger 61 and the outer poppet therefore moves away from its seat 38 in response to the force which fluid in the system port 238 exerts upon the front end of the outer poppet 42.

The flow restricting plunger 61 is an elongated tubular member which is freely slidable in the bore 46 in the front of the main poppet member, with a small clearance, so as to move rearwardly in response to the rearward flow of fluid through said bore when the pilot poppet opens. Extending coaxially forwardly from the valve element 54 of the pilot is a conical projection 63 which is adapted to be partway received in the rear end of the tubular plunger 61 when the latter is in its rearmost position, to substantially close the rear of the tubular plunger while allowing restricted flow from passage 33 to the chamber 45 through the clearance space between the plunger 61 and the bore 46 in the front of the outer poppet. It will be apparent, however, that pressure of fluid in the service passage 33 and hence the system port 238 is manifested upon the front end of the plunger 61 and is transmitted by the plunger to the pilot poppet to aid in holding the latter unseated until pressure in the service passage drops back down below its predetermined relief value.

It will be appreciated that the coaction of the pilot poppet and the flow restricting plunger 61 assures smooth, chatterfree unloading action of the valve mechanism 39, prevents it from "cracking" before pressure in the line passage reaches the relief value for which it is adjusted, and enables it to close promptly when such pressure drops back down below its predetermined relief value.

When the pilot poppet is closed the tubular plunger 61 remains in a forward position in which a circumferential flange 64 thereon near its rear end engages the bottom 65 of the counterbore in the outer poppet member. The plunger 61 is lightly biased to this normal forward position, in which its rear end is spaced from the projection 63 on the pilot poppet, by means of a small coiled compression spring 66 which reacts between the flange 64 on the plunger 61 and the inner tubular member 52. In this normal position of the plunger 61, which it of course maintains when the valve mechanism opens in response to a rise in pressure in the main section 137 of the transfer passage 37 to a value above that obtaining in the system port 238, said plunger permits substantially unrestricted flow of fluid between the pressure chamber 45 and the system port 238.

The operation of the cross line relief mechanism of this invention will now be apparent and can be briefly summarized as follows. Assume that the spool 14 of the control valve 6 is shifted to its left hand operating position, causing pressure fluid to be diverted to the right hand side of the cylinder 25 so as to actuate the motor 7 and a load L connected therewith to the left. If the valve spool is now abruptly returned to its neutral or "hold" position shown in FIGURE 1, the inertia of the load tends to keep the piston 24 of the hydraulic motor

moving toward the left, imposing upon the left hand line 12 a fluid pressure which might be dangerously high if not relieved, and tending to draw a void in the right hand line 12.

The high fluid pressure in the left hand line passage 33 and system port 238, which connect with the left hand duct 12, is likewise manifested in the pressure chamber 45 of the left hand valve mechanism 39 due to the communication of said pressure chamber with the left hand line passage through the bore of the tubular plunger 61. Assuming that this fluid pressure is of sufficiently large magnitude to unseat the pilot poppet, the opening of the pilot poppet permits fluid to exhaust from the pressure chamber 45 of the left hand valve mechanism, through the pilot valve seat, around the rear of the outer poppet member, and into the main section 137 of the transfer passage. When such flow of fluid through the pilot valve seat 51 begins, the tubular plunger 61 will be carried rearwardly into engagement with the plug-like projection 63 on the pilot poppet to restrict the flow of fluid from the left hand line passage 33 into the chamber 45, and the outer poppet will move off of its seat in response to the force which fluid in the system port 238 exerts upon its front end, to permit fluid to flow from the left hand line passage into the main section of the transfer passage. The outer poppet member of the left hand valve mechanism will remain unseated as long as pressure in the left hand service passage exceeds the predetermined relief setting for the pilot poppet of the left hand valve mechanism.

It will be appreciated, of course, that whenever the pressure rises to an abnormally high value in the left hand line passage due to the inertia of the load, as mentioned hereinbefore, there will be a corresponding pressure decrease in the right hand line passage and danger of drawing a void in the right hand line 12. Hence, at the time fluid at such abnormally high pressure in the left hand line passage is relieved into the main section of the transfer passage, the pressure of fluid in the right hand line passage will have decreased by an amount proportional to the increase in pressure in the left hand line passage, and this decrease is likewise manifested in the pressure chamber of the right hand valve mechanism. Consequently, as soon as fluid at increased pressure in the main section 137 of the transfer passage exceeds that of fluid at decreased pressure in the right hand line passage, the outer poppet member of the right hand valve mechanism moves rearwardly off of its seat in response to the force which fluid in the main section of the transfer passage exerts upon the forwardly facing surface 49 of the outer poppet. Thus both valve mechanisms will be promptly opened to permit flow of fluid from the left hand line passage into the right hand line passage through the transfer passage until such time as pressure in the left hand line passage drops below the relief value setting of the left hand valve mechanism 39.

Obviously if the direction of motion of the inertia load were reversed, the mechanism of this invention would similarly permit cross line relief flow of fluid from the right hand line passage to the left hand one.

As indicated earlier, the cross line relief mechanism 6 of this invention may be employed in a hydraulic circuit apart from the control valve thereof, in which case the ports 34 would be eliminated and the motor ports 36 of the mechanism would be connected with the cylinder separately from but in parallel with the connections to the control valve 6.

From the foregoing description taken together with the accompanying drawings it will be apparent that this invention provides a cross line relief mechanism for a reversible hydraulic motor wherein a single transfer passage provides for flow of fluid in either direction between line passages connected with opposite sides of the motor, and wherein flow of fluid through said transfer passage is con-

trolled by a pair of combined high pressure relief and void control valves which assure stable, chatter-free operation of the cross line relief mechanism and provide for smooth deceleration of the hydraulic motor connected with the mechanism.

What is claimed as my invention is:

1. In a hydraulic control instrumentality of the type comprising a body having a pair of line passages each connectable with one side of a reversible hydraulic motor, cross line relief means for transferring hydraulic pressure fluid from either line passage in which an abnormally high pressure develops to the other line passage, comprising:
  - (A) a transfer passage in the body to communicate the line passages with one another and connecting only therewith;
  - (B) annular valve seats in the transfer passage, one for each line passage, spaced from one another along the length of the transfer passage and each defining a connecting passage through which its line passage is communicable with the transfer passage, said valve seats facing in the direction that fluid flows therethrough from the line passages to the transfer passage;
  - (C) and a bi-directional valve unit mounted in the body at a location opposite each valve seat, and wholly outside its line passage, said valve units comprising:
    - (1) a poppet means in each valve unit projecting forwardly therefrom into the transfer passage toward its valve seat for cooperation therewith and to normally block fluid flow through the connecting passage defined thereby,
    - (2) means in each valve unit responsive to pressure of fluid at an abnormally high value in its line passage for effecting rearward actuation of its poppet means to establish relief flow of fluid through its connecting passage to the transfer passage,
    - (3) and means in each valve unit responsive solely to the pressure of such relief fluid in the transfer passage for effecting rearward actuation of its poppet means to enable such relief fluid in the transfer passage to flow through its connecting passage to the associated line passage.
2. A hydraulic control instrumentality comprising the combination of:
  - (A) a body having a pair of line passages adapted for connection with the opposite sides of a reversible fluid motor;
  - (B) a transfer passage in the body connecting said line passages with one another and communicating only therewith;
  - (C) annular valve seats in the transfer passage, one for each line passage, through which the latter are communicated with the transfer passage, said seats being spaced from one another along the length of the transfer passage and facing away from their line passages;
  - (D) a pair of valve mechanisms, one for each valve seat;
  - (E) means mounting the valve mechanisms in the body at locations wholly outside the line passages and opposite their respective valve seats;
  - (F) one of said valve mechanisms comprising a high pressure relief valve which projects forwardly into the transfer passage for engagement with its valve seat and which opens in response to pressure of fluid at an abnormally high value in its line passage to establish relief flow of such fluid to the transfer passage;
  - (G) and the other of said valve mechanisms comprising a reverse acting check valve which projects forwardly into the transfer passage for engagement with its seat and which is caused to open solely in response to the pressure of said relief fluid in the transfer pas-

sage at times when the relief valve opens, so as to thus permit pressure fluid to flow serially through both valve seats from the line passage associated with said relief valve to that associated with the check valve, said check valve opening in a direction counter to such flow of relief fluid through its seat so as not to obstruct such flow to its associated line passage.

3. The hydraulic control instrumentality of claim 2, wherein each of the valve mechanisms comprises a high pressure relief valve as well as a reverse acting check valve, so as to enable pressure fluid from either line passage in

5 which an abnormally high pressure obtains to flow through the transfer passage to the other line passage.
